DOMESTIC APPLIANCE

Robert R. Candor, Oakwood, Ohio, assignor to
General Motors Corporation, Dayton, Ohio, a
corporation of Delaware

Application July 11, 1947, Serial No. 760,411

6 Claims. (Cl. 161—1)

1

This invention relates to domestic appliances, and more particularly to automatic clothes washing machines.

An object of this invention is to provide an automatic clothes washing machine which has a filling period of time, an agitating period of time, and a spinning period of time, and is provided with simple, and readily operable means for varying any one of these periods of time independently of the other period of time.

Another object of this invention is to provide an automatic washing machine having filling, agitating, and spinning periods of time, in which the agitating period of time may be shortened independently of either the filling period or the spinning period.

Another object of this invention is to provide an automatic washing machine having a plurality of agitating periods of time interspersed within filling and spinning periods, and in which one of the agitating periods of time may be varied independently of another agitating period.

Further objects and advantages of the present invention will be apparent from the following description, reference being had to the accompanying drawings, wherein a preferred form of the present invention is clearly shown.

In the drawings:

Fig. 1 is a diagrammatic representation, partly in vertical cross-section, of the washing machine and its controls;

Fig. 2 is a front view of part of Fig. 1;

Fig. 3 is a diagrammatic representation of the timer control, in combination with the electrical elements of the machine;

Fig. 4 is a diagrammatic representation of the timer in combination with the switches used to select the fractional time and the particular operations to be shortened;

Fig. 5 is a front diagrammatic view of the control dial of the timer, indicating the actuation of the contacts;

Fig. 6 is a diagrammatic representation of the multiple speed windings of the timer motor;

Fig. 7 is a diagrammatic representation, similar to Fig. 3, but showing a modified form; and

Fig. 8 is a diagrammatic representation of a further modification.

The washing machine without shortened fill, agitation or spin

A washing machine includes a tub 50, which may be centrifugally rotated to dry the clothes. An agitator 51 may be placed inside of the tub, for agitating the clothes prior to the centrifugal

action. The tub 50 and agitator 51 are actuated through the medium of a transmission 52, which is actuated by a motor 53, the transmission being controlled by a solenoid 54. When the motor 53 is energized, together with the solenoid 54, the agitator is not reciprocated; but the tub 50 is centrifugally rotated at sufficient speed to wring the clothes. When the motor 53 is energized while the solenoid is deenergized, the agitator 51 is reciprocated. When the solenoid 54 is deenergized while the tub 50 is rotating, a braking action is applied to the tub 50, to stop it quickly. Any type of motor and transmission may be used for accomplishing this purpose, such, for example, as is disclosed in the patent to Kendall Clark, No. 2,422,395, granted June 17, 1947.

An access door 56 is provided for introducing the clothes and detergent into the tub 50. A door switch 57, hinged at 18 and closing contacts at 17, is actuated by the rod 58 so that the contacts 17 are closed whenever the door 56 is opened, and vice versa.

A timer 70 is provided, which controls the flow of electrical power from the lines L₁ and L₂ to the various electrical elements of the washing machine. The washing machine is filled with water from the hot water connector 60 and a cold water connector 59. These connectors discharge into a thermostatic mixing valve 61. The hot water connector also discharges into a hot water line 71. The mixing valve 61 discharges into a mixed water line 72. The lines 71 and 72 are controlled by solenoid valves 63 and 62 respectively, and discharge into a common outlet chamber 64. This chamber is connected by a line 73 to a constant pressure valve 65, which maintains a constant pressure of water on the line 74, which in turn discharges through a fixed orifice 66 and a nozzle 67 at a constant flow rate into the tub 50. The arrangement is such that the timer 70 opens the selected solenoid valve 62 or 63 for a sufficient length of time so that the constant volume discharge of water at the nozzle 67 fills the tub 50 to the correct level during each filling operation. The position of the handle 87 of the selector switch 88 determines whether the movable contact 89 of the switch 88 contacts 15 or 16. When the handle 87 is on the indication "Hot" contact 89 engages 15, and the hot water solenoid 63 is energized for the first filling operation. During the second and third filling operations, the mixed water solenoid 62 is energized regardless of the position of contact 89.

Fig. 3 shows the timer construction diagrammatically. It includes a timer motor 20 which moves a small gear 21 intermittently such as at one-half minute intervals. This gear in turn actuates a larger gear 22, which is fixed to a rotatable shaft 23. The shaft 23 carries a plurality of rotatable cams 24, 25, 26 and 27 which are in engagement with movable blades 28, 29, 30 and 31 respectively, and which carry movable contacts 6, 4, 11 and 8 respectively. The cams 24, 25, 26 and 27 have been indicated by dotted circles; but it is understood that they actually are irregularly shaped cams, so shaped that the movable contacts 6, 4, 11 and 8 are actuated at selected intervals of time, as indicated in Fig. 5. Fig. 5 shows the indications on the knob 36, which are inside of the circle 35. The numerals on the outside of circle 35 indicate the positions of the movable contacts at the various intervals of time, as the shaft 23 is rotated clockwise. The knob 36 is provided with an irregular orifice 37 which fits over the irregular end 38 of the shaft 23. The knob 36 is axially secured to the shaft 23, so that, when the knob 36 is moved slightly axially, a movable contact 2 is moved into and out of contact with stationary contact 1, the movable contact 2 being carried by a movable blade 39 which has its upper end in axial engagement with the shaft 23. Whenever the knob 36 is pulled towards the operator, the contacts 1 and 2 are opened, and whenever the knob is pushed away from the operator, the contacts 1 and 2 are closed. A suitable snap acting mechanism is provided for allowing the shaft to be placed in these two axial positions. This may take the form of a double grooved ring 40 carried by the shaft 23 in which a spring-pressed pin 41 rides, so that the ring 40 snaps from one position to the other.

Whenever the movable contact 8 engages contact 9, the solenoid 54 is energized, so that the tub 50 is centrifugally rotated. However, since the switch 57 is closed whenever the door 56 is open, and switch 57 is in parallel with solenoid 54, all electrical elements are automatically de-energized, should the door 56 be open, or opened, during a period which normally is a spin period, as more fully hereinafter explained. Therefore, should the operator open the door while a centrifugal action is taking place, all operations are automatically stopped, including the operation of the timer. Also, if the door 56 should be left open during any previous operation, then, when the timer reaches a spin position, all operations, including that of the timer, are automatically stopped. The machine then remains inoperative until the operator closes the door 56, at which time the operations of the machine, including the timer, are resumed when they were automatically stopped by the open door.

Normally, when the door 56 is closed and the contacts 1 and 2 are closed in the inward position of knob 36, the energization of the various elements is as follows:

When 8 is on 7, one of the water solenoids 62 or 63 (depending on the selection at 89) is energized to introduce water (hot or tepid) into the tub 50. The electric current flow is from L₁, 1, 2, 100, 31, 8, 7, 102, 89 and, if 87 is on "hot," 15, 103, 63, 104, 105, 14, 13 to L₂. Should the handle 70 87 be on "mix," then the current branches from 89 to 16, 106, 62, 107, 105, 14, 13 to L₂.

When 8 is on 9 current flows from L₁, 1, 2, 100, 31, 8, 9, 108, 109, 54, 110, 105, 14, 13 and L₂. This energizes the spin solenoid 54 and causes rotation 75

of tub 50. However, should the door 56 be open, or be opened, while 8 is on 9, then, instead of causing a rotation of tub 50, all operations are stopped by the flow of current from L₁, 1, 2, 100, 31, 8, 9, 18, 57, 17, solenoid 111, 13 and L₂. The energization of solenoid 111 pulls the safety switch 13 from 14. This allows current to continue to flow through solenoid 111; but disconnects all other electrical elements, 54, 63, 62, 53 and 20 from L₂, thus stopping all operations, including the timer, as long as the door 56 is open and the timer is on a "spin" position. When the door 56 is closed, switch 57 is opened, and solenoid 111 is deenergized, thus allowing safety switch contacts 13 and 14 to close on each other by spring action into their normally closed position. It should be noted that this control of the door 56 over the electrical circuits can only take place during a "spin" position of the timer, since that is the only time that contact 8 is on 9, and is the only time that solenoid 111 can be energized.

When 11 is on 10 (which never occurs while 8 is on 7) tepid water solenoid 62 is energized. Electric current flows from L₁, 1, 2, 112, 30, 11, 10, 113, 106, 62, 107, 105, 14, 13, to L₂. The tub 50 is filled with tepid water to the correct level during such an operation.

When 11 is on 12, the running winding of motor 53 is energized. Electric current flows from L₁, 1, 2, 112, 30, 11, 12, 114, 53, 115, 105, 14, 13, to L₂.

When 4 is on 3, the timer motor 20 is energized. Electric current flows from L₁, 1, 2, 116, 117, 3, 4, 29, 118, 20, 105, 14, 13 to L₂.

When 6 is on 5 the starting winding of motor 53 is energized. Electric current flows from L₁, 1, 2, 116, 119, 5, 6, 28, 120, 53, 115, 105, 14, 13 to L₂.

In the operation of the device, without shortened fill agitation or spin periods, the door 56 is opened and clothes and detergent are placed in the tub 50. The door then should be closed and the knob 36 should be pushed away from the user to close contacts 1 and 2 and the knob 36 should be turned clockwise from the "off" position S (where the timer previously had stopped) to the start position at A. Just before reaching position A, the cams are actuated so that contact 3 closes on 4 and contact 7 closes on 8 as indicated at A'. This energizes the hot water solenoid and starts the flow of hot or tepid (as selected) water into the tub 50 to the correct level. At the same time the timer motor 20 is energized. The shaft 23, and knob 36 are then intermittently progressed from position A to position B, where contact 8 is moved away from 7; 6 is moved to 5; and 11 is moved to 12. This energizes the starting coil of motor 53. It also energizes the running coil of motor 53. The motor 53 is therefore started and caused to run on the starting running windings thereafter. Since the transmission solenoid 54 is deenergized, the agitator 51 is agitated. After a suitable interval of time, as at C, the starting winding of the motor 53 is deenergized by opening contacts 5 and 6. The washing operation continues, (agitator action) for the selected number of minutes, until the position D is reached. Should the user desire a shorter washing period than the 10 minutes indicated on the timer, he may advance the knob 36 manually to a shorter period, such as to an 8, 6 or other minute period. When position D is reached contacts 5 and 6 are closed, as are also 8 and 9. The closing of contacts 8 and 9 energizes solenoid 54, if the door 56 is closed, and starts

65 The washing operation continues, (agitator action) for the selected number of minutes, until the position D is reached. Should the user desire a shorter washing period than the 10 minutes indicated on the timer, he may advance the knob 36 manually to a shorter period, such as to an 8, 6 or other minute period. When position D is reached contacts 5 and 6 are closed, as are also 8 and 9. The closing of contacts 8 and 9 energizes solenoid 54, if the door 56 is closed, and starts

the tub 50 to spin. The starting winding of the motor 53 is again energized by the closing of contacts 5 and 6 because acceleration is necessary, and the motor is slowed down to a speed requiring the starting winding to aid in getting the tub up to speed. However, should the door 56 be opened while the spinning operation progresses or if the door had been left open, then no spinning of the tub can take place, and all operations of the machine, including that of the timer are interrupted by the opening of contacts 13 and 14 as previously described. The spinning operation empties the water in the tub 50 into sump 130 from whence it flows through pipe 131 and pump 132 into drain connector 133.

As the timer continues, the position E is reached where the starting winding is deenergized by the opening of contacts 5 and 6. When the position F is reached contact 8 is moved from 9 and 11 from 12. This deenergizes the solenoid 54 and the motor 53 and stops the spinning of tub 50. At position G 10 is closed on 11. This energizes the mixed water solenoid 62 and starts flow of mixed water through the nozzle 67. The flow of water continues until position H, which is the correct length of time to fill the tub. At H, contact 11 is moved from 10 while the contacts 5 and 6, and 11 and 12 are closed. This stops the flow of water and energizes the starting and running windings of the motor 53 to reciprocate the agitator 51. At I, contact 6 is moved from 5, thus deenergizing the starting winding of motor 53, the motor 53 continuing to run on the running winding. From H to J, the agitator 51 is reciprocated. At J contact 6 closes on 5 while contact 8 closes on 9. If the door 56 is closed, the tub 50 starts to spin; but if the door is already open, then the tub does not spin and all operations cease until the door is closed, when they are resumed where they were stopped. At K the starting winding is deenergized by the opening of contacts 5 and 6. At L the spinning operation is terminated by the opening of contacts 8 and 9 and 11 and 12. At M the mixed water solenoid is opened by the closing of contacts 10 and 11. The filling operation continues until N is reached. The tub has then been filled with tepid water. At N, contacts 10 and 11 are opened while 5 and 6, and 11 and 12 are closed. This stops the filling operation and starts the reciprocation of the agitator, the motor 53 running on both its starting and running windings. At O the starting winding is deenergized by the opening of contacts 5 and 6. At P the contacts 5 and 6 are closed as are also contacts 8 and 9. This starts a spinning operation, the motor 53 running on both windings until position Q, when the starting winding is deenergized by the opening of contacts 5 and 6. At R the spinning operation is terminated by the opening of contacts 8 and 9 and 11 and 12. It should be noted that, if the door 56 should be opened at any time during the interval between P and R the spinning operation will be stopped together with the timer. If the door had been left open before the reaching of this spinning operation, the basket will not spin and the timer will stop.

After the spinning operation P to R, the timer continues to run until position S is reached when the contacts 3 and 4 are opened, thus deenergizing the timer motor 20. At this time the entire washing operation is terminated and the clothes may be removed from the machine. The knob 36 remains at S until the machine is used again.

The opening of the door 56 does not interfere with the timer operation.

with any of the filling or agitating operations A to D, F to J, and L to P. However, should the door 56 be open at, or be opened during, the spinning operation, all of the operations of the machine, including the timer operation, are stopped. These operations are resumed upon the closing of the door 56. This allows the user to inspect the interior of the machine at all times except when spinning is taking place. He can even inspect the machine during the spinning operation; but that operation is stopped until the door is closed.

The foregoing description of the washing machine, without shortened fill, agitation or spin starting with column 1, line 17, is described and claimed in the copending application of Harold B. Wallis and Duane R. Neal, S. N. 561,857, filed November 4, 1944.

The washing machine with shortened operation of fill, agitation or spin

The following are improvements made by applicant whereby any of the filling, agitating and spinning operations may be shortened to any one or more fractions of the normal operations.

The filling, agitating and spinning operations may be shortened, with respect to the corresponding normal operations, by increasing the speed of the timer 20. For this purpose, the timer 20 may be provided with a normal speed winding 200, a higher speed winding 201, and a highest speed winding 202. Thus three speeds are indicated; but it is to be understood that this is illustrative and any plurality of speeds may be used. By way of example, the ratio of speeds of the windings may be as 1, $\frac{1}{2}$ and 3 respectively. This establishes a normal period of time, and $\frac{1}{2}$ period of time and a $\frac{1}{3}$ period of time respectively. For the purpose of selectively energizing the windings 200, 201, and 202, the lead lines 203, 204, and 205 are provided, which are selectively energized by the operation of the solenoid armatures 206 and 207. When the solenoids are not energized, normal operation takes place; but when one or more of the solenoids are energized, the periods of time are shortened, by increasing the speed of rotation of the timer 20, as will be more fully hereinafter pointed out. A timer having multiple speeds is disclosed in my copending application S. N. 701,116, filed October 4, 1946, of which this application is a continuation-in-part.

For the purpose of selecting whether the periods of time shall be shortened to $\frac{1}{2}$ or to $\frac{1}{3}$, a three position switch 208 is provided. When the switch 208 is in the center position, the switch is open and neither of the solenoid structures 206 or 207 may be energized, and therefore no period of time is shortened. When the switch 208 is in the "one-third" position, shown in full lines in Fig. 3, then the solenoid structure 207 may be energized, and this will shorten any selected period of time to $\frac{1}{3}$ of its normal period of time, since the winding 202 would be energized. When the switch 208 is moved to the "two-thirds" position, which is the left hand position in Fig. 3, then the selected periods of time will be shortened to $\frac{1}{2}$ normal, because the solenoid structure 206 would be energized, and the winding 201 correspondingly would be energized.

For the purpose of shortening the spin period, a switch 209 is provided. This establishes a circuit from the spin line 109, through switch 209, switch 210 (when in low position), solenoid winding 211 or 211a (depending on the position of

switch 208) and line L₂, thus raising armature

207 during the spin period, and shortening it to its shortest period by reason of the energization of winding 201 or 202 of timer motor 20. However, since it may be desirable not to shorten the starting period of the motor 53, a solenoid 212 is provided, which is energized from the line 213, which is connected with the starting line 120, and L₂, thus preventing the energization of solenoid 211 during the starting period of motor 53. This insures that the motor 53 is completely up to speed before its spin period is shortened.

To shorten the agitation, a switch 214 is provided. This switch is connected through line 215, with the motor running winding 114 and establishes a circuit through either the solenoid 216 or 217, depending upon the position of switch 208. A solenoid 218 is interposed between the spin line 109 and L₂, which raises the solenoid switch 219 during the spinning operation, thus preventing the spinning operation from being shortened by the closing of switch 214, but permitting the agitation period to be shortened, since the solenoid 218 is not energized at that time.

To shorten the hot water filling period, a switch 220 is provided between the hot water line 103 and either of the solenoids 221 or 222 (depending on the position of switch 208). Thus the hot water filling period is shortened to $\frac{1}{3}$ or $\frac{2}{3}$, by the closing of switch 220.

To shorten the tepid, or mixed filling period, a switch 223 is interposed between the tepid control line 113 and the solenoids 224 and 225. Thus, depending upon the switch 208, the tepid filling period may be shortened to $\frac{1}{3}$ or $\frac{2}{3}$ its normal filling time.

Fig. 6 indicates diagrammatically a type of multiple speed motor that may be used for the timer 20. Thus the multiple speed windings 200, 201 and 202 cooperate with proper segmental armatures 230, 231 and 232 to rotate the timer motor shaft 233 at varying speeds, as previously indicated.

In the operation of the device shown in Figs. 1 through 6, with selectively shortened periods of time for fill, agitation, or spin, the user first selectively places any one or more of the switches 88, 208, 209, 214, 220 and/or 223, to the desired position, as indicated in Fig. 4, and then the timer operating knob 36 may be moved to the start position, at which time the proper solenoid 62 or 63 is energized to start the filling operation, and the timer motor 20 is energized. Depending upon the position of the switches, as heretofore described, any one of the fill, agitation or spin periods may be shortened to $\frac{1}{3}$ or $\frac{2}{3}$ its normal time by the energization of timer windings 201 and 202 instead of 200, since the proper solenoids are energized for this purpose. It is not necessary, and it would be too involved, to trace each and every possible circuit capable of being selected, and therefore no attempt is made to indicate how these circuits are established, it being obvious from the drawings, how these circuits are established.

In Fig. 7, the operation and construction of the various devices designated by reference numerals below 200 are the same as previously described under the heading "The washing machine without shortened fill, agitation or spin," or as described in the aforesaid application of Wallis and Neal. Reference numerals above 300 are used to designate improvements for shortening any selected operation. In Fig. 7 it is shown how to shorten, for example, either the first agitation, by itself, or in combination with the second and third agi-

tations, or in combination with any other selected operation to be shortened in lieu of the second and third agitations.

For this purpose, a desired number of additional timer cams 303 and 304 are added to the timer shaft 23. For example, the cam 303 moves the contact blade 305 to the left during the first agitation period, and maintains it to the right throughout the remainder of the operations. The cam 304 moves the contact blade 306 to the left during the second and third agitation periods, and maintains it to the right throughout the remainder of the operations. Examples of changes in the agitation periods have been given; but it is to be understood that any other periods may be used, such, for example, as the fill period.

The blade 305 is electrically connected to the stationary contact 307 of a switch 308, which is connected to the contact blade 29. The other stationary contact 309 of the switch 308 is connected by line 310 with one terminal of the normal winding 301 of the timer 20. The construction is such that with the switch 308 set on 309, the timer 20 operates at normal speed throughout all operations. When it is desired to shorten the selected operations, the switch 303 is placed on contact 307. Thereafter, during the first agitation period current flows through the blade 305 and contact 311, through line 311a, to a faster running winding 302 of the timer 20. Thus, during the first agitation period, the timer operates at a faster rate and shortens the first agitation period if the switch 308 is set on 307.

To shorten an additional operation, or additional operations, the switch 312 may be connected to stationary contact 314 and may be placed on stationary contact 313, which is connected with blade 306. When the blade 306 is to the left the timer again operates at a faster rate, since the faster timer winding 302 is energized through line 311a. However, when the washing machine is operating at any other operation than the agitation periods, the normal timer winding 301 is energized, since current flows from 308 through 307, 305, 314, 312, 313, 306, 315 and normal winding 301. This provides for normal periods of fill and spin; but shorter periods of agitation. However, if it is only desired to shorten the first wash period and maintain the remainder of the operations normal, the switch 312 is placed on stationary contact 316, so that the timer 20 is then operated at a faster rate only during the first agitation period, and thereafter energizes the normal winding 301 through contact 314, switch 312, contact 316, line 317 and winding 301.

In the operation of the modifications shown in Fig. 7, the operator sets the switch 308 on contact 307 if he wishes to shorten the first agitation period, or places it on 309 if he wishes to have all operations of normal duration. In addition, he places switch 312 on contact 313 if he wishes to shorten the second and third agitation periods, or places the switch 312 on the contact 316 if he wishes to maintain all of the operations normal, except the first agitation. Thereafter he advances the knob 36 to the start position and moves it axially inward, if not previously so moved, and thereafter the machine operates as previously described, with the exception that the first agitation period is shortened, and the second and third agitation periods are shortened or not shortened as selected.

Fig. 8 shows a further modification in which any one or all of the operations may be shortened

independently of the remainder. In this modification the timer 20 and the shaft 23 are connected with the washing machine and wiring diagram indicated by the reference numerals below 300 and their operation is identical with the elements heretofore described under the heading "The washing machine without shortened fill, agitation or spin" or as described in the aforesaid application of Wallis and Neal. The improvements are indicated by numerals above 300.

Thus, additional cams 350, 351, 352 and 353 are mounted on the timer shaft 23, and are provided, respectively, with contact blades 354 to 357 inclusive. Each of the cams 350 to 353 moves its corresponding blade to the left during its respective period, or periods, of operation, and maintains its blade to the right during the remaining operations. Thus cam 350, if it is to correspond with the fill operations, moves the blade 354 to the left during all of the fill operations, and maintains it to the right during the remaining operations. The cam 351, if it corresponds to the first agitation, moves blade 355 to the left during the first agitation and maintains it to the right during the remaining operations. Cam 352, if it corresponds to the second and third agitations, moves the blade 356 to the left during the second and third agitations and maintains it to the right during the remaining operations. The cam 353, if it corresponds to the spin operations, moves blade 357 to the left during the spin operation, and maintains it to the right during the remaining operations. The number and character of the cams indicated is by way of example only, and the number and character may be varied as desired.

The blade 29 is electrically connected with the blade 354 by the wire 358. The stationary contacts 359, 360 and 361 are electrically connected respectively with the blades 355, 356 and 357. The contact 362 is connected, through lines 363 and 364 with normal timer winding 365. Thus whenever all of the blades 354 through 357 are to the right, the timer motor 20 operates at normal speed, since the circuit is from blade 29 through blades 354 to 357 and contacts 359 to 362, and lines 363 and 364 to normal timer winding 365.

Selector switches 366 through 369 are connected with the stationary contacts 370 through 373 respectively. These selector switches may be applied on any one of the "normal," stationary contacts 374 through 377 respectively. These normal contacts are connected with the line 364, which is connected with the normal timer winding 365. Thus the user can place any one of the selector switches 366 through 369 on the "normal" contacts 374 through 377 and have the particular operation corresponding thereto operated at normal length of time. On the other hand, the selector switches are also provided with "shorter" contacts 378 through 381 respectively, which are connected with the line 382, which leads to the faster timer winding 383. When any one of the selector switches 366 through 369 are placed on the corresponding "shorter" contact, that particular operation is operated at a shorter time. The selector switches 366 through 369 are also provided with "shortest" contacts 384 through 387 respectively, which are connected with the line 388 leading to the fastest timer winding 389. The user may, therefore, operate any one or more of the operations at the shortest time by placing the particular selector switch on its "shortest" contact.

In the operation of the modification shown

in Fig. 8, the operator places any of the desired selector switches 366 through 369 at any one of the desired "normal," or "shorter," or "shortest" contacts and then moves the timer knob 36 to the start position, and moves it inward if necessary. Thereafter the washing machine operates in the usual manner, except that the particular operation so selected will be shortened in a manner depending on the position of the selector switches. Any one of the operations may be selected to be "normal," "shorter" or "shortest."

While three timer windings, four selector cams and four selector switches have been specifically shown and described, in Fig. 8, by way of example, it is to be understood that such numbers may be varied, as desired.

While the form of embodiment of the invention as herein disclosed, constitutes a preferred form, it is to be understood that other forms might be adopted, as may come within the scope of the claims which follow.

What is claimed is as follows:

1. A timer comprising: a driving motor having a plurality of running windings and a plurality of armatures cooperatively imparting a plurality of running speeds to said motor; a set of contacts opened and closed by said motor to control the duration of a plurality of different operations of an independently powered mechanism; and a manually adjustable switch in series with one of said contacts selectively connecting said last named contact with said running windings preselectively to vary the duration of said different operations.

2. A timer comprising: a driving motor having a plurality of running windings and a plurality of armatures cooperatively imparting a plurality of running speeds to said motor; a set of contacts opened and closed by said motor to control the duration of a plurality of different operations of an independently powered mechanism; and a plurality of manually adjustable switches each in series respectively with a different contact of said set of contacts selectively connecting said last each said different contact with said running windings preselectively to vary the duration of said different operations.

3. A timer comprising: a driving motor having a plurality of running windings and a plurality of armatures cooperatively imparting a plurality of running speeds to said motor; a first set of contacts opened and closed by said motor and controlling the energization of said motor; a second set of contacts opened and closed by said motor and controlling the flow of energy to a device to be controlled to cause said device to perform a plurality of different operations; and a manually adjustable switch in series with one of the contacts of said first set of contacts selectively connecting said one of the contacts with said running windings preselectively to vary the duration of said different operations.

4. A timer comprising: a driving motor having a plurality of running windings and a plurality of armatures cooperatively imparting a plurality of running speeds to said motor; a first set of contacts opened and closed by said motor and controlling the energization of said motor; a second set of contacts opened and closed by said motor and controlling the flow of energy to a device to be controlled to cause said device to perform a plurality of different operations; and a plurality of manually adjustable switches each in series respectively with a plurality of con-

tacts of said first set of contacts selectively connecting said plurality of contacts with said running windings preselectively to vary the duration of said different operations.

5. A timer comprising: a driving motor having a plurality of running windings and a plurality of armatures cooperatively imparting a plurality of running speeds to said motor; a knob operated rotatable and axially movable cam shaft intermittently rotated by said motor; a set of contacts opened and closed by said shaft to control the duration of a plurality of different operations of an independently powered mechanism; a plurality of manually adjustable switches each in series respectively with a plurality of said contacts selectively connecting said last named contacts with said running windings preselectively to vary the duration of said different operations; and a master switch controlling the flow of energy to said timer opened and closed by 20 axial movement of said shaft.

6. A timer comprising: a driving motor having a plurality of running windings and a plurality of armatures cooperatively imparting a plurality of running speeds to said motor; a knob operated rotatable and axially movable cam shaft intermittently rotated by said motor; a first set of contacts opened and closed by said shaft and controlling the energization of said motor; a second set of contacts opened and 25 30

closed by said shaft and controlling the flow of energy to a device to be controlled to cause said device to perform a plurality of different operations; a plurality of manually adjustable switches each in series respectively with a plurality of contacts of said first set of contacts with said running windings preselectively to vary the duration of said different operations; and a master switch controlling the flow of energy to said timer opened and closed by axial movement of said shaft.
